UNITED STATES PATENT OFFICE.

WILLIAM Z. W. CHAPMAN, OF NEW YORK, N. Y.

IMPROVEMENT IN APPARATUS FOR INHALING GASES.

Specification forming part of Letters Patent No. 44,075, dated September 6, 1864.

To all whom it may concern:

Be it known that I, WILLIAM Z. W. CHAPMAN, of the city, county, and State of New York, have invented certain new and useful apparatus for administering gas, vapors, or medicines to patients for medical and surgical purposes; and I do hereby declare and ascertain my said invention, which I call the "Anæsthetic Respirator," referring in said description to the accompanying drawings, in which—

Figure 1 is a perspective view; Fig. 2, a section; Fig. 3, a cross-section through the indicator.

The object of my improvements is to obviate the difficulties and objections heretofore encountered in administering nitrous oxide or other gases or vapors, &c.

The mode heretofore in general use for this purpose is to fill an ordinary india-rubber bag with the gas, the bag being furnished with a breathing-faucet, consisting of a common stop-cock with a flattened end to enter the mouth of the patient. When used, the lips of the patient are required to be held tightly by an assistant, around the breathing-pipe, to prevent the introduction of atmospheric air, and the loss of gas as the patient becomes insensible. It also requires that the nose be held by the operator for the same reason. In this condition the patient is held until the desired effect is produced by breathing from and into the bag or reservoir. At each exhalation of the lungs it will be noticed the carbonic acid thrown off enters the bag, and the patient is forced to breathe it over again, with the gas thereby diluted, inhaling a poisonous compound, very hurtful and injurious. By this method, too, saliva or blood is often profusely discharged from the mouth into the bag, which renders this manner of administering the gas most disgusting and objectionable. An improvement has heretofore been attempted on the breathing-faucet by adding thereto a metal plate to cover the lips, and thus prevent the introduction of air or escape of gas; but this is found inefficient, for when the muscles of the lips relax in the process of taking the gas and become flaccid the shield has no control over them, and is useless therefor. My improved apparatus is intended to obviate all these objections, as well as some others found in practice.

The description in detail is as follows, of

one form of construction, it being understood that changes and modifications can be made without changing the character of the invention—such, for instance, as the substitution of any known form of valve that will properly open and close the passage, instead of the one here described. Some of the parts may be omitted without destroying the efficiency of the rest, as the saliva-valve or even the pipe itself; but I prefer all the parts together. To convey the gas from the reservoir, (which is placed at any desirable distance from the patient,) I employ a flexible pipe, (lettered *a*.) This pipe communicates directly and freely with the gas-holder at one end. At the other a short rigid tube, *c'*, is affixed, having a four-way stop-cock, *c*, therein, and a handle attached thereto, by which it is held in the hand of the operator. The stop-cock is kept closed by a spring or other proper device, and is opened by the thumb acting on a thumb piece, *b*, which is in a convenient position therefor, near the handle. Instead of a spring to close the stop-cock, it may be closed by the thumb on the lever. The spring is, however, preferable, as it guards against loss of gas at all times. The tube *c'* is connected with the mouth-piece by a flexible joint, *d*, or otherwise, and for convenience in construction, cleaning, and repair it should be removable. The mouth-piece is made of a tube, *e*, which forms a part of the gas passage. The end that enters the mouth may be flattened. On this is fitted a tongue-piece, *e'*, having its under side extended, so as to lay over the tongue, and curved upward, with its orifice on the upper side, which guards against its being stopped by the tongue. This tongue-piece should be removable for cleaning. Next the tongue-piece on tube *e* is a plate, *f*, affixed somewhat oblong, and so curved as to approximate to the form of the space between the lips and the gums, which space it occupies when the apparatus is used. This supports the lips which are over it, however flaccid they become, and as they fall against it they involuntarily exclude the outer air. In addition to this plate *f*, I employ, when necessary, a shield, *g*, to prevent blowing out the gas around plate *f* when exhaling the breath. This shield *g* is formed like the plate *f*, and is made to slide from and toward it on tube *e*. It can be set up with a screw, or otherwise, to press gently

upon the lips and hold them between it and plate *f*. Above tube *e*, I fit a nose-piece, *h*, which in the drawings consists of a cup surrounded by a hood to inclose the nose. A short pipe, *h'*, may unite the nose-piece with the pipe *e*, (and the nose-piece may connect with the saliva-pipe,) and the gas or breath can freely pass through it. The pipe *h'* extends up into the cup to guard against the discharge of mucus from the nose into the breathing-pipe *e*. Other modifications of the nose piece may be made—such as a bifurcated pipe to enter the nostrils or rest against them; or a rigid cap can be made with a flexible edge to fit the nose tight, and the nose-piece, or a part thereof, can be hinged so as to turn back. These are obvious changes that need no particular description.

In addition to the parts just described for inhaling gas, &c., I add an exhaling-pipe, *i*, which connects with and opens into the tube *e'*, when the valves have shut off the gas therefrom, (see section Fig. 2,) by which a direct communication is opened with pipe *i* from the mouth. A flexible tube leads from pipe *i* to a reservoir that may contain caustic potash (but this is no part of my invention) to purify it. In addition to the above-named pipes and flexible tubes I affix a third pipe, *k*, that communicates with the breathing-tube on the under side, between the stop-cock or valve *e* and the mouth. This is for the purpose of conveying away any saliva, mucus, or blood that may be discharged from the mouth into a proper receiver. This pipe may or may not have a valve to close it in addition to the valves or stop-cock before named. When employed as at *l* in the drawings, it should be so connected with *e* as to move with it, so that when the stop-cock *e* opens the passage *a*, communicating with the gas-holder, the passage to the saliva-pipe *k* and exhaling-pipe *i* will be closed, and vice versa. When the patient draws in the breath, the passage to tube *a* must be open. When the breath is exhaled, it must be closed and the passage to pipes *i* *k* opened. It would be easy to make the opening and closing of these valves at the proper time depend upon the breathing of the patient; but this might require too great exertion, particularly with sick and feeble persons. I therefore prefer using such

valves as are readily moved by the hand of operator, one example of which I have described with modifications indicated.

The operation is as follows: When the patient is ready to inhale, the operator opens with his thumb the passage to the gas holder. As soon as the patient stops inhaling, the operator closes this passage and opens the others. The patient then exhales. This operation is continued until the desired effect is produced with as little effort to the patient as breathing the natural way. To indicate the inhaling or exhaling of the patient to the operator, I place an indicator on the tube *e'* at *n*. This indicator consists of a little wing or throttle-valve suspended by its upper edge to an axis within the tube, as clearly seen in Fig. 3, the axis projecting beyond the pipe outside, to which a light hand is attached, so as to indicate the direction of the current within. The indicator may be made in several other ways—such as a diaphragm, water-column, or the like, it simply being necessary to have an indicator of any known description at that point to direct the action of the operator.

Having thus fully described my improvements, what I claim as new, and desire to secure by Letters Patent, is—

1. The employment of the plate *f*, affixed to the tube *e*, placed within the lips, as and for the purposes described.
2. In combination with the above, the shield *g*, for the purposes herein set forth.
3. In combination with the breathing-tube *e*, the tongue-piece *e'*, substantially as described.
4. In combination with the breathing apparatus, the nose-cover, all as herein specified.
5. The arrangement and operation of the valves, in combination with the breathing-tubes, substantially as and for the purposes herein set forth.
6. The indicator, substantially as and for the purposes described.
7. The separate pipe for saliva, &c., all as herein specified.

WM. Z. W. CHAPMAN.
